UNITED STATES PATENT OFFICE.

KELLY I. FRANKLIN, OF TILLAMOOK, OREGON.

SAWMILL TRACK ADJUSTER.

Application filed November 12, 1923. Serial No. 674,272.

To all whom it may concern:

Be it known that I, KELLY I. FRANKLIN, a citizen of the United States, residing at Tillamook, in the county of Tillamook and 5 State of Oregon, have invented certain new and useful Improvements in Sawmill Track Adjusters; and I do declare the following to be a full, clear, and exact description of the invention, such as will enable others 10 skilled in the art to which it appertains to make and use the same.

In mounting saw mill carriages, two parallel rails are employed, said rails being supported upon a pair of sills. One of these 15 rails is usually flat to co-operate with carriage rollers having transversely straight treads, while the other rail is formed with a longitudinal rib or the like for reception in grooves of other carriage rollers, so that 20 the rib and the grooved rollers co-operate in guiding the travel of the carriage. It often happens however that the ribbed rail, from one cause or another, gets materially out of line, which causes the mill to produce 25 poor work. It is the object of my invention, to provide simple and inexpensive means whereby the ribbed rail may be laterally adjusted upon its supporting sill, so that it may at all times be kept in proper 30 alinement, regardless of irregularities in the sill.

With the foregoing in view, the invention resides in the novel subject matter herein- 35 after described and claimed, the description being supplemented by the accompanying drawing.

Figure 1 is a transverse sectional view 40 through the ribbed track rail and its supporting sill, showing in elevation one of the adjusters associated with said track and sill.

Fig 2 is a view similar to Fig. 1 but cut in a different plane.

Figure 3 is a fragmentary plan view, and 45 the plane upon which Fig. 2 is cut, is indicated by the line 2—2 of this Figure 3.

Figure 4 is a fragmentary side elevation 50 of the ribbed track and its supporting sill, showing the association of one of the adjusters therewith.

Figure 5 is a vertical sectional view on 55 line 5—5 of Fig. 2.

Figure 6 is a side elevation of the track- 60 adjusting block and its oppositely extending threaded studs.

In the drawing above briefly described, the 65 numeral 1 designates a supporting sill for

a ribbed track rail 2, but instead of spiking or bolting the rail to the sill in the usual manner, I connect the two by means of the improved adjusters. In the preferred 60 form of construction, each adjuster includes an elongated metal plate 3 inset in the upper side of the sill 1 and extending transversely thereof, said plate being secured in place by spikes, lag-screws or the like 4. The plate 65 3 is provided with a slot 5 which extends longitudinally of said plate but transversely of the sill 1, said slot slidably receiving a substantially rectangular block 6 having a seat or recess 7 for receiving and holding the base 70 of the track rail 2. The block 6 is provided with oppositely extending threaded studs 8, and the sill 1 is transversely grooved as indicated at 9, to slidably receive said block and studs. 75

The ends of the plate 3 are provided with downwardly extending abutments 10 which are apertured to receive the studs 8, one abutment being preferably formed with an opening 11 of circular form, while the other is provided with a slot 12 opening through its lower end, these shapings for the apertures, being employed in order that the device may be easily assembled. Nuts 13 are 80 threaded on the studs 8 in contact with the outer sides of the abutments 10 and it will be seen that by loosening one nut and tightening the other, the rail 2 may be adjusted laterally to the necessary extent. Tightening 85 of the first loosened nut, will then tightly 90 clamp the rail in place. It is of course understood that the adjusters are used at suitably spaced points throughout the length of the track rail 2 and it will be seen that by properly setting said adjusters, the rail may 95 be kept in accurate alinement, to permit the production of best results by the mill or other machine upon which the adjusters are used.

As excellent results are obtainable 100 from the details disclosed, they are preferably followed, but within the scope of the invention as claimed, numerous minor changes may be made and obviously the invention is not restricted in use to saw mills, but may be employed wherever it will be of 105 advantage.

I claim:

1. A track rail adjuster comprising a slot- 110 ted plate adapted to extend across the upper side of a sill, apertured abutments extend- ing downwardly from the ends of said plate for contact with the vertical sides of the

sill, a block slidably received in the slot of said plate and having provision for holding a rail, studs extending oppositely from said block through the aperture of said abutments, and nuts threaded adjustably on said studs in contact with the outer sides of said abutments.

2. In combination with a sill having a transverse groove in its upper side, a plate 10 extending across the upper side of said sill over said groove and having a slot therein disposed opposite said groove, abutments extending downwardly from the ends of said

plate in engagement with the edges thereof and being apertured opposite the ends of 15 said groove, a block slidable in said groove and said slot and provided with means to hold a rail, studs projecting from the opposite ends of said block and passing through the apertures in said abutments, and nuts 20 threaded on said studs and engaging the outer sides of said abutments.

In testimony wherof I have hereunto affixed my signature.

KELLY I. FRANKLIN.
